UNITED STATES PATENT OFFICE.

LOUIS WILPUTTE, OF NEW ROCHELLE, NEW YORK, ASSIGNOR OF TWO-THIRDS TO
ALICE A. WILPUTTE, OF NEW ROCHELLE, NEW YORK.

COKE QUENCHING AND HANDLING APPARATUS.

1,380,453.

Specification of Letters Patent.

Patented June 7, 1921.

Application filed February 6, 1920. Serial No. 356,622.

To all whom it may concern:

Be it known that I, Louis Wilputte, a citizen of the United States, and resident of New Rochelle, in the county of Westchester and State of New York, have invented certain new and useful Improvements in Coke Quenching and Handling Apparatus, of which the following is a specification.

10 The general object of my present invention is to provide simple and effective means for receiving and quenching the hot coke discharged from retort coke ovens and, after the coke is quenched, for transporting 15 it away from the receiving and quenching apparatus.

The various features of novelty which characterize my invention are pointed out with particularity in the claims annexed to 20 and forming a part of this specification. For a better understanding of the invention, however, and the advantages possessed by it, reference should be had to the accompanying drawings and descriptive matter 25 in which I have illustrated and described a preferred embodiment of my invention.

Of the drawings:

Figure 1 is a transverse section of a by-product coke oven battery;

30 Fig. 2 is a similar section of a portion of the apparatus shown in Fig. 1 but taken on a larger scale;

Fig. 3 is a plan view of the battery; and

35 Fig. 4 is a plan view of a portion of the apparatus of Fig. 3 on a larger scale than the last mentioned figure.

In the drawings I have illustrated the use 40 of my invention in connection with a by-product coke oven battery A of conventional type. The battery is formed with horizontal coking chambers A', extending transversely to the length of the battery and provided at their ends with doors A². At the coke or discharge side of the battery there is 45 provided a platform or bench A³ running lengthwise of the battery and having its upper surface flush with the bottoms of coking chamber A'. At its outer edge the bench A³ merges into an inclined coke receiving 50 wharf F which may be a reinforced concrete structure, preferably having its upper side faced with cast iron plates F¹. At the lower edge of the inclined wharf F are pillar walls F² and F³ running lengthwise of the battery and serving 55 spaced apart to form a chamber O prefer-

ably formed at its bottom with a narrow drain trough or channel O'. As shown the lower edge of the wharf F is supported by the wall F² and the wall F³ is more remote from the battery. A series of gates G extend longitudinally along the lower edge of the wharf F, and in its closed position, shown in full lines in Figs. 2 and 3, each of these gates prevents the coke on the adjacent portion of the wharf F from sliding off. As shown each gate is connected by hinge pivots G' to brackets G⁴ which extend from the wall F³ onto the adjacent edge of the wharf F and are arranged one between each pair of gates G. In the particular construction shown each gate comprises a plurality of curved bars G² which in the closed position of the gate have their lower ends bearing on the upper side of the wharf. Advantageously the gates are provided with counter weights G³ to facilitate their operation by a workman standing on a platform J'.

The coke wharf stops short of the wall F³ thus providing a slot like opening O² in the top of the chamber O across which the brackets G⁴ extend. To bridge this gap when coke is being discharged from the wharf a series of movable plates or bridge members H are provided. As shown there is one of these bridge members for each gate G. Each bridge member as shown is connected by pivots H' to the corresponding brackets G⁴, so that it may turn back and forth between the dotted and full line positions shown in Fig. 2. In its dotted line 90 position each bridge H forms an extension of the coke wharf extending across the opening O² and the top of the wall F³. Each bridge member H is provided with an operating handle H² by means of which the bridge member may be moved between its two positions by a workman on the platform J'.

Advantageously each bridge member H is so pivoted that it is gravity held in either 100 of the two positions into which it may be adjusted. The coke passing from the wharf F across a bridge member H, when this bridge member and the corresponding gate G are adjusted into the positions shown in 105 dotted lines in Fig. 2, is discharged onto a conveyer J shown as a belt conveyer running lengthwise of the battery and serving to convey the coke received by it to a screening, carloading, or other receiving station 110

for the quenched coke. Advantageously a coke feeder 1 of known type is provided to directly receive the coke passing off the wharf and distribute it uniformly onto the 5 conveyer J. The conveyer J is located between the platform J' and the wall F³ and the coke feeder 1 is movable along a track-way to position it first adjacent one gate G and then another according to conditions.

10 Running lengthwise of the battery, adjacent the lower edge of the wharf is an elevated platform or wharf M on which an operator may stand while quenching coke resting on the wharf F. K represents a pipe 15 supplying water for the coke quenching operation and L represents a flexible hose for manipulation by the operator on the platform M. A series of these pipes L may be permanently connected each through a cut 20 off valve to the pipe K at suitable intervals along the length of the battery, or a pipe K may be provided with valved connections for the ready attachment of a single hose pipe L which may be thus connected to the 25 pipe K first at one point and then at another. At the end of the battery a sump O¹ is provided into which the drain channel O' at the bottom of the chamber O empties. Above the platform or bench A³ 30 there is provided a track E' extending longitudinally of the battery from which is suspended a coke guide E of known type.

In operation when the charge in one of the chambers A' is fully coked, the corresponding doors A² are removed and the charge of coke is pushed out of the coking chamber through the guide E and onto the wharf F by the pusher ram C of a pusher machine D which may be of any well known 40 type. As the coke is pushed through the guide E it distributes itself in a tolerably uniform layer X on the top of the wharf F adjacent the mouth of the coking chamber A' being discharged provided the inclination of the wharf is but slightly in excess 45 of the angle required to permit the coke to slide off the wharf. At this time the gates G at the lower edge of the adjacent portion of the wharf are closed. The charge of coke 50 is next quenched while on the wharf by discharging water onto it from the pipe K. Any surplus water not vaporized by heat of the coke, which is red hot when pushed onto the wharf F drains off the wharf and 55 into the chamber O, the corresponding bridge members H being then in their full line positions shown in Fig. 2. The water thus discharged into the chamber O falls to the bottom of the latter and is carried out 60 of the chamber through the channel O'. The channel O' is preferably made narrow as shown, so that the velocity of the water will be great enough to carry away any coke breeze carried into the chamber O with the 65 quenching water.

Advantageously vent openings F⁵ are formed in the wall F² so that steam and vapor rising from the water in the chamber O may escape in large measure through these ports to the space beneath the wharf 70 F rather than out through such portions of the opening O² as may be open.

With the apparatus described the coke may be quenched practically as soon as pushed, thus avoiding any such delay in the 75 quenching operation as is normally involved when the usual quenching car is provided for receiving the hot coke and transporting it to a quenching station at the end of the battery. The coke pushed onto the inclined 80 wharf spreads out into a tolerably uniform and relatively thin layer thus facilitating the rapid and uniform quenching of the coke with a minimum of water. The provision of the drainage chamber O receiving excess 85 water, between the lower edge of the coke wharf proper and the conveyer J with the adjustable bridge members H eliminates all possibility of this excess water splashing on the conveyer or running into the trench in 90 which the conveyer will normally be located. It will be understood that in practice immediately adjacent ovens are discharged at intervals of some hours, so that when any one oven is pushed there will normally be no 95 coke lying on the wharf F in the vicinity of the oven being discharged. The coke handling apparatus disclosed is relatively inexpensive to construct and economical in the ground space required for its installation.

While in accordance with the provisions of the statutes, I have illustrated and described the best form of embodiment in my invention now known to me, it will be apparent to those skilled in the art that changes may be made in the form of apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. The combination with an inclined coke quenching wharf of a wall adjacent the lower edge of the wharf, but separated therefrom by a slot like space, gate members 105 movable into and out of the position in which they prevent coke from sliding off the wharf, and bridge members movable from one position in which they form extensions of the wharf projecting beyond said wall 110 into a second position in which they permit the ready passage of excess quenching water running off said wharf through said space.

2. The combination with an inclined coke quenching wharf of a wall adjacent the 115

lower edge of the wharf, but separated therefrom by a slot like space, gate members movable into and out of the position in which they prevent coke from sliding off the 5 wharf, and bridge members hinged to swing from one position in which they form extensions of the wharf projecting beyond said wall into a second position in which they permit the ready passage of excess quenching water running off said wharf through 10 said space.

3. The combination with a battery of horizontal coke ovens, of an inclined coke wharf at one side of the battery, a coke conveyer 15 running along the lower edge of the wharf, means regulating the passage of coke from said wharf onto said conveyer and a drainage channel adjacent the conveyer on the battery side of the latter adapted to receive 20 coke quenching water running off the lower edge of the wharf.

4. The combination with a battery of horizontal coke ovens, of an inclined coke wharf at one side of the battery, a coke conveyer 25 running along the lower edge of the wharf, means regulating the passage of coke from said wharf onto said belt, a drainage channel adjacent the conveyer on the battery side of the latter, one side wall of which is 30 closer to the conveyer than is the edge of the wharf, and members movable from one position in which they form extensions of the coke wharf projecting beyond the drainage channel into another position in which 35 they permit quenching water running off

the wharf to pass into said drainage channel.

5. The combination with a battery of horizontal coke ovens, of an inclined coke wharf at one side of the battery, a coke conveyer 40 running along the lower edge of the wharf, means regulating the passage of coke from said wharf onto said belt, a drainage channel adjacent the conveyer on the battery side of the latter, one side wall of which is 45 closer to the conveyer than is the edge of the wharf, members movable from one position in which they form extensions of the coke wharf projecting beyond the drainage channel into another position in which they permit 50 quenching water running off the wharf to pass into said drainage channel; a platform running along the lower edge of the wharf and quenching water supply means operable from said platform. 55

6. The combination with a battery of horizontal coke ovens, of an inclined coke wharf at one side of the battery, a coke conveyer running along the lower edge of the wharf, means regulating the passage of the coke 60 from said wharf onto said conveyer, and a drainage channel adjacent the conveyer on the battery side of the latter adapted to receive coke quenching water running off the lower edge of the wharf, said channel 65 being restricted at its bottom.

Signed at New York in the county of New York and State of New York this 30th day of January A. D. 1920.

L. WILPUTTE.
